SHEET METAL BRAKE

Richard L. Berkson, Encino, Calif., assignor to
 Berkroy Products, Inc., Burbank, Calif., a corporation of California

Application July 6, 1949, Serial No. 103,198

1 Claim. (Cl. 153—16)

1
 This invention relates to a bending brake for sheet metal, and more particularly to improvements in the structure, relationships and combinations of parts of such bending brakes, so as to provide a compact ensemble having a wide range of adjustments and uses, as well as affording ease of adjustment and operation.

One of the objects of my invention is to provide a bending brake for sheet metal which embodies a movable clamping jaw for holding a workpiece in place during bending, and has a manually operable handle and coacting structure for actuating the clamping jaw and for keeping it in a substantially level position while raised to a released position.

Another object of the invention is to provide a bending brake for sheet metal embodying a single and readily adjustable element for determining the angle of bend of a workpiece within a wide range of limits.

My invention has for a further object the provision of a bending brake for sheet metal which incorporates a leaf bar having a portion which is removable, when desired, to reduce the limit of distance between reverse bends.

It is also within the purview of this invention to provide a bending brake for sheet metal having screw adjustments for determining the radius of the bend produced in the sheet metal workpiece.

As another object, my invention comprehends the provision of a bending brake for sheet metal which includes manually operable and readily accessible adjusting elements for selecting the position of a clamping jaw, so as to determine the thickness of the workpiece which will be gripped and released by manual operation of a clamping jaw actuating lever.

Other objects and advantages of the invention will be apparent from the following description and the accompanying drawings in which similar characters of reference indicate similar parts throughout the several views.

Referring to the two sheets of drawings:

Fig. 1 is a top plan view of a bending brake for sheet metal which embodies a preferred form of my invention;

Fig. 2 is a front elevational view of the bending brake shown in Fig. 1;

Figs. 3 and 4 are fragmentary end elevational views of the bending brake taken from the opposite ends thereof; and

Fig. 5 is a fragmentary end sectional view drawn to a larger scale than Figs. 3 and 4 and wherein different operating positions of the

2
 parts are depicted in the solid and dot and dash lines.

Having reference to the accompanying drawings, the exemplary embodiment of my invention which is disclosed for illustrative purposes includes a base 12 which, in the disclosed structure, is internally hollow and includes bottom and top walls 13 and 14 and a rear wall 15, so as to provide substantial height to the structure for bench mounting, when desired. The top wall has a substantially flat upper surface 16 which serves as a table for supporting workpieces. Also, the top wall 14 has a substantially straight forward edge 17 which intersects the flat top surface 16 to form a straight and relatively sharp corner 18. At the opposite ends of the base, end plates 19 and 20 are secured thereto by removable fastening means, such as cap screws 22 and 23 and have outwardly projecting flanges 24 and 26 adapted to use in securing the bending brake to a suitable support.

An apron 26, which is preferably in the form of a flat plate having a straight edge 21 and a hollow reinforcing rib 28 secured to and extending along a surface thereof adjacent the base 12, has coaxial studs 29 and 30 secured to the opposite ends thereof and journaled in aligned bearings 32 and 33 in the end plates 19 and 20 respectively. The axis of the studs 29 and 30 and the bearings 32 and 33 extends substantially along the corner 18 on the base, so that the apron is hingedly supported for limited rotational movement about that corner of the base. As depicted in Fig. 5, end reinforcing partitions, such as 34, in the base 12 have notches 35 therein to accommodate the reinforcing rib 28. In order to provide a strong end and reinforcing structure for the apron 26, relatively heavy blocks 36 and 37 have opposing channels 38 and 39 respectively therein, which channels receive opposite end marginal portions of the apron. The studs 29 and 30 extend into and are secured to the blocks 36 and 37. Further to reinforce the apron for the bending of relatively heavy sheet metal, a leaf bar 40 is secured to the front face thereof adjacent the edge 27. In order, however, that the leaf bar may be removed for the purpose of making reversed bends at a minimum distance apart, removable fastening means, such as screws 42, are utilized for securing the leaf bar to the face of the apron. In the normal position of the apron, as depicted in Fig. 5, the edge 21 of the apron and a side 43 of the leaf bar are in substantially

coplanar relationship to the top surface 16 of the base. A bar 44 is secured to the block 36 and normally extends downwardly at one end of the apron to provide a handle by which the apron is swung upwardly during a bending operation by the application of manual force thereto.

For controlling the limit of upward swinging movement of the apron 26, thereby to control and make possible the repetition of angular bends in sheet metal within a wide range of limits, I have provided an adjustable stop mechanism 45 which is shown in Figs. 1, 2 and 3. This stop mechanism includes an eccentric cam 46 secured to an end of the stud 29 which projects outwardly of the end plate 19. Fastening means, such as a pin 47, is utilized to prevent relative rotation between the stud 29 and the cam 46, as well as to establish fixed relative positions of those parts. A block 48 is secured to the end plate 19 at a position near, but spaced from the cam 46 by means such as a locating stud 49 and a cap screw 50. A thumb screw 52 is threaded into the block 48 at a position and in a direction such that it is aligned for the abutment of one end thereof with the eccentric surface of the cam 46. Preferably, a lock nut 53 is provided on the thumb screw 52 to secure that thumb screw in a fixed position after adjustment.

The shape and normal position of the cam 46 relative to the stud 29 and the apron 26 are selected so that when the apron hangs in its normal position, as illustrated in Figs 3, 4 and 5, the low portion of the cam faces the end of the thumb screw 52. In the direction of the normal movement of the cam 46 during the upward swinging movement of the apron 26, the eccentric surface of the cam 46 gradually departs from the axis of the stud 29 through a relatively large angle (for example 135 degrees). Thus, when the thumb screw 52 is to be set for a relatively small angle of swinging movement of the apron, the end of that thumb screw is set to a position relatively close to the normal position of the cam, and which position is determined by trial to provide the desired angle of bend. When the angle of bending movement is larger, the thumb screw is set to a position more remote from the surface of the cam. In either instance, the abutment of the cam surface with the end of the thumb screw 52 provides a positive stop for the upward swinging movement of the apron.

As another adjustment which is utilized to determine the position of a bend in a sheet metal workpiece of predetermined size, and to facilitate repetition of the positions of such bends in additional workpieces, parallel rods 54 and 55 have their ends threaded into the rear of the base 15 near the upper surface 16 thereof and project rearwardly therefrom. A stop bar 56 extends across the parallel rods 54 and 55, and has openings therein which slidably receive those rods, so that the stop bar is adjustable toward and from the rear of the base to a position which is a selected distance from the corner 18 at the front of the base. Locking elements 57 and 58, such as thumb screws, are threaded into the stop bar 56 for engagement with the rods 54 and 55 to secure the stop bar in an adjustable position along the rods. By preference, a support plate 59 is secured to the stop bar 56, so that its upper surface is substantially at the level of the upper surface 16 of the base, thereby to

provide support for the end portion of a workpiece which is abutted against the stop bar.

A clamping jaw 60 which is utilized to hold a workpiece firmly in place against the upper surface 16 of the base includes a relatively rigid bar 62 having a forwardly projecting flange portion 63 and extends practically from end-to-end of the base above the upper surface 16 and in substantially parallel relationship to the corner 18. At the rear of the lower surface of the bar 62, a heel plate 64 is secured thereto and is substantially coextensive therewith. This heel plate, in the disclosed structure, includes a longitudinal recess 65 extending along the forward surface thereof and which forms a channel with the lower surface of the flange 63. Forward clamping elements 66 have tongues along their rear edge which fit into the channel provided by the groove 65 when the upper surfaces of those clamping elements are disposed against the surface of the flange 63. The clamping elements 66, as shown in Fig. 1, are of varied widths and together extend across practically the full span of the flange portion 63 in abutting relationship. Cap screws 68 are threaded into the clamping elements and extend through the flange portion 63 to hold the clamping elements in place. One or more of the clamping elements may be removed, when desired, to facilitate the bending of short pieces and pieces having previously bent ends, and the like. Some of the cap screws 68 extend through slots 69 and 70 near opposite ends of the flange portions 63, so that the positions of the clamping elements may be varied and adjusted relative to the rigid bar 62. In the disclosed structure, front surfaces 72 of the clamping elements form an acute angle with the lower clamping surface of those elements, so as to provide for a wide range of bends which can be formed around the bending edge 67 thereof.

At the opposite ends of the flange 63 of the clamping jaw 60, blocks 73 and 74 are secured thereto by fastening means, such as cap screws 75. These blocks have coaxial studs such as 76 projecting outwardly therefrom at opposite ends of the clamping jaw and extending into slots such as 77 in movable lifting blocks 78 and 79. The lifting blocks, in turn, have bearings 80 and 82 respectively, therein, which bearings fit into eccentrics 83 and 84. The eccentrics are secured to opposite end portions of a shaft 85 which extends through the base and is journaled in the end plates 19 and 20. At one end of the shaft 85, a handle 86 is secured thereto and projects angularly from the shaft for effecting rotational movement of that shaft thereby to produce movements of the lifting blocks which, in turn, move the clamping jaws toward and from the upper surface 16 of the base. The eccentrics 83 and 84 at the opposite ends of the shaft are, of course, aligned, so that they produce like and corresponding movements of both lifting blocks and both ends of the clamping jaw. A stop pin 87 is secured to and projects outwardly from the end plate 20 in alignment with the handle 86, in order to limit the movements of the eccentrics and their respective lifting blocks.

In the disclosed structure, the slots 77 into which the studs 76 extend are elongated in a direction extending toward the axis of the shaft 85. Also, thumb screws 88 and 89 are threaded into the ends of the lifting blocks and extend into the ends of the slots in a direction corresponding to that of the elongation of the slots.

These thumb screws provide an adjustment by which the clamping position of the clamping jaw may be varied in reference to the upper surface 16 of the base when the eccentrics 83 and 84 are at a position, such as that illustrated in Fig. 5, in which those eccentrics will hold the clamping jaw in a gripping position against a workpiece.

As an additional support for the clamping jaw in respect to one of the lifting blocks, which additional support is adapted to maintain the clamping jaw in a relatively level position with respect to the upper surface 16 of the base while it is raised, I have provided a pin 98 which projects outwardly from one side of the lifting block 79 and which is aligned for engagement with a pin 92 which projects outwardly from one end of the heel plate 64 on the clamping jaw. The pins 98 and 92 engage during upward movement of the lifting blocks to raise the rear part of the clamping jaw. On the other hand, the pin 98 which projects from the lifting block 79 is below the pin 92, so that those pins do not interfere with the clamping action which is effected through downward movement of the lifting blocks, as produced by the eccentrics 83 and 84.

A further adjustment is provided for determining the position of the clamping jaw in relation to the corner 18 of the base, so as to make allowance for various thicknesses of workpieces being bent. For effecting this latter adjustment, posts 93 and 94 are secured to the rear surface of the base at the opposite ends thereof by fastening means such as cap screws 95. These posts extend upwardly beyond the upper surface 16 of the base and have slots 96 and 97 therein through which hand screws 98 and 99 extend in a direction such that they are threaded into opposite ends of the heel plate 64 with their opposite and manually operable end portions exposed at the rear of the base. Also, opposed channels 100 and 102 are provided on opposite sides of the slots 96 and 97, slidably to accommodate peripheral protuberances 103 and 104 on the mid-portions of the hand screws 98 and 99 respectively. Preferably, and as indicated in Fig. 5, compression springs 105 are mounted in the lower ends of the slots to exert some lifting force against the protuberances on the hand screws, thereby to avoid binding of the hand screws in their respective slots during movements of the clamping jaw. It may be observed that the hand screws 98 and 99 determine the proximity of the bending edge 67 on the clamping jaw to the corner 18 on the base, while being free to move with the clamping jaws as different workpieces are clamped and removed.

In the operation of the disclosed bending brake, a workpiece is inserted between the upper surface 16 of the base and the clamping elements 66 of the clamping jaw, so that the line of the bend is between the corner 18 of the base and the bending edge 67 at the forward ends of the clamping elements. The hand screws 98 and 99 are adjusted to provide a desired radius of bend for metal of the thickness which is being bent.

The thumb screws 88 and 89 are adjusted to effect firm clamping of the workpiece between the clamping jaw and the base without continually exerting clamping force upon the handle 86 during the bending operation. With the workpiece thus held, the apron 26 is swung upwardly as indicated in dot and dash lines 26a, in Fig. 5, by manual force applied to the handle 44. The upward swinging movement of the edge 27 of the 10 apron bends the metal around the bending edge 67 of the clamping elements. If reversed bends are desired at a spacing closer than the combined thicknesses of the apron 26 and leaf bar 40, that leaf bar may be removed. Setting of 15 the angle of the bend is effected by adjustment of the thumb screw 52, so that it stops movement of the apron at a desired position as it is swung upwardly.

While I have illustrated a preferred embodiment of my invention, many modifications may be made without departing from the spirit of the invention, and I do not wish to be limited to the precise details of construction set forth, but desire to avail myself of all changes within the 25 scope of the appended claim.

Having thus described my invention, what I claim as new and desire to secure by Letters Patent of the United States, is:

In a bending brake for sheet metal, the combination comprising a base providing a flat top surface and a straight edge, an apron provided with axially aligned studs at opposite ends, means providing bearings supporting said studs for rotational movement at positions such that the apron 30 is swingable substantially about a line of intersection of the flat top and straight edge of the base, and stop means for determining the limit of swinging movement of the apron in one direction, said stop means including an eccentric cam 35 secured to one of the studs, and a stop screw adjustably mounted in alignment for abutment with the eccentric cam.

RICHARD L. BERKSON.
